(57) **CLAIM**

The ornamental design for a landscape edger, as shown and described.

DESCRIPTION

FIG. 1 is a perspective view of a landscape edger showing the new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and,

FIG. 7 is an opposite side elevational view thereof.

The evenly spaced broken lines depict portions of the landscape edger that form no part of the claimed design. The dot dash broken lines depict the bounds of the claimed design and form no part thereof.

1 Claim, 5 Drawing Sheets(56)
